Primary Examiner — Darlington Ly(74) *Attorney, Agent, or Firm* — Che-Yang Chen; Law Office of Michael Chen(57) **CLAIM**

The ornamental design for an adult tricycle, as shown and described.

DESCRIPTION

FIG. 1 is a perspective view of the adult tricycle showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 1;

FIG. 11 is an enlarged view of a portion indicated with numeric 11 in FIG. 2; and,

FIG. 12 is an enlarged view of a portion indicated with numeric 12 in FIG. 2.

The broken lines shown in the drawings are included for the purpose of illustrating portions of the adult tricycle that form no part of the claimed design.

1 Claim, 12 Drawing Sheets(56)
